UNITED STATES PATENT OFFICE.

JOSEPH H. GLAUBER, OF CLEVELAND, OHIO.

DESIGN FOR A BODY FOR SILL COCKS OR VALVES.

SPECIFICATION forming part of Design No. 33,860, dated January 8, 1901.

Application filed December 10, 1900. Serial No. 39,438. Term of patent 7 years.

To all whom it may concern:

Be it known that I, JOSEPH H. GLAUBER, a citizen of the United States, residing at Cleveland, in the county of Cuyahoga and State of Ohio, have invented and produced a new and original Design for a Body for Sill Cocks or Valves, of which the following is a specification, reference being had to the accompanying drawings, forming part thereof.

Figure 1 is a side elevation of a sill cock or valve embodying my new design, and Fig. 2 is a side elevation thereof at right angles to Fig. 1. Fig. 3 is a plan view of the design.

The leading or material feature of my new design as thus shown lies chiefly in the surface configuration of the body thereof, the same having its surface relieved by a series of ribs and panels 2, extending entirely around

the same and lying between the decorative crown 3 at their tops and the annular flange 4 at their bottoms.

The said design is further marked by a lateral branch 6, having its terminal surface relieved with threads 7, and the said branch and body are alike finished with an ornamental roughened surface original in this design.

What I claim is—

The design for a body for a sill cock or valve, substantially as herein shown and described.

Witness my hand to the foregoing specification this 4th day of December, 1900.

JOSEPH H. GLAUBER.

Witnesses:

M. A. SHEEHAN,
R. B. MOSER.
